UNITED STATES PATENT OFFICE

106,076

DESIGN FOR A HEMATOLOGICAL CASE

James Alfred Wilson and Norman S. Hobson,
Meriden, Conn., assignors to Bard-Parker
Company Inc., Danbury, Conn., a corpora-
tion of New York

Application August 4, 1937, Serial No. 70,845

Term of patent 14 years

To all whom it may concern:

Be it known that James Alfred Wilson and Norman S. Hobson, citizens of the United States and residents of Meriden, in the county of New Haven and State of Connecticut, have invented a new, original, and ornamental Design for a Hematological Case, of which the following is a specification, reference being had to the accompanying drawing forming a part thereof, in which

The figure is a view in perspective of a hema-

logical case showing my new design, the lock being shown conventionally in dotted lines.

Both sides of the case are identical in appearance. The rear end of the case is plain except that it is crossed by the wide flat rib shown in contour at the rear end of the figure.

We claim:

The ornamental design for a hematological case substantially as shown and described.

J. ALFRED WILSON.
NORMAN S. HOBSON.
